UNITED STATES PATENT OFFICE.

FRANK J. MELLADY, OF NEW YORK, N. Y.

GAS-RANGE ATTACHMENT.

1,140,994.

Specification of Letters Patent. Patented May 25, 1915.

Application filed June 23, 1914. Serial No. 346,340.

To all whom it may concern:

Be it known that I, FRANK J. MELLADY, a citizen of the United States, residing at New York, in the county of New York and State of New York, have invented new and useful Improvements in Gas-Range Attachments, of which the following is a specification.

The invention relates to gas range attachments, and more particularly to the class of shields or protectors for stop cocks.

The primary object of the invention is the provision of a shield or protector wherein the stop cocks on gas ranges or stoves will be concealed so as to avoid access thereto, thereby making it impossible for the accidental opening of the stop cocks by children or the person using the range or stove, thus avoiding any possibility of the leakage of gas when the burner or burners are not lit.

Another object of the invention is the provision of a shield or protector which permits access to the stop cocks on the opening of the said shield or protector, the latter being of novel construction to enable the same to be mounted on any style or type of gas range or stove without requiring alterations therein or the employment of extra parts.

A further object of the invention is the provision of a shield or protector of this character which is extremely simple in construction, reliable and efficient in its purpose, and inexpensive in manufacture.

With these and other objects in view, the invention consists in the construction, combination and arrangement of parts as will be hereinafter fully described, illustrated 40 in the accompanying drawing, and pointed out in the claim hereunto appended.

In the drawing: Figure 1 is a front elevation of a gas range, showing the shield constructed in accordance with the invention applied thereto. Fig. 2 is an enlarged sectional view on the line 2-2 of Fig. 1. Fig. 3 is a sectional view on the line 3-3 of Fig. 1. Fig. 4 is an inner face view of the shield.

Similar reference characters indicate corresponding parts throughout the several views in the drawing.

Referring to the drawing in detail, 55 designates a gas range of ordinary construction, having the ordinary gas supply pipe

6 which is provided with stop cocks 7 controlling the flow of gas to the burners on top of the range. A portion of this pipe 6 is disposed at the front of the range, and such portion lies horizontally a slight distance below the top of the range, as is usual, and to which is connected the shield or protector hereinafter fully described. 60

The shield or protector comprises a pair of substantially U-shaped end brackets 8, 65 each carrying on its lowermost limb a clip 9 which is connected thereto by means of bolt members 10, the same being passed through the clip and limb of the bracket 8 for the clamping of the bracket to the horizontal portion of the gas supply pipe 6, the clip and limb being bowed as at 11 to conform to the cross sectional shape of the pipe 6, while the other limb of the bracket 8 forms a rest for a swinging cover or top 70 section 12 hingedly connected to the horizontal stationary top section 13 of the shield or protector, the same being formed with a solid vertical front 14 and a solid horizontally disposed bottom 15, so that 75 when the top section 12 is in lowered position the stop cock 7 will be concealed and inaccessible until the swinging top section 12 is raised so that access can be had to the stop cock for the opening thereof or closing of the same as is usual. 80

The hinges for the swinging section 12 each comprises a tongue 16 secured to or integral with the said top section, while the stationary top section 13 is formed with 85 slots 17 which receive the tongues 16, the latter being bent into substantially hook-shape so that the free ends thereof underlie the said top section 12, and in this manner 90 the latter section is connected with the stationary top section 13 for swinging movement. It is of course to be understood, however, that the particular form of hinges 95 can be varied if found desirable.

Mounted on the swinging top section 12 100 is a hand knob 18 which permits the convenient raising and lowering thereof, the stationary top section 13, front and bottom 105 14 and 15, respectively, of the shield are riveted or otherwise secured to the brackets 8, and when the swinging top section 12 is closed it rests upon the uppermost limbs of the said bracket. 110

From the foregoing it is thought that the construction and manner of use of the 110

device will be clearly understood, and therefore a more extended explanation has been omitted.

What is claimed is:—

- 5 A shield of the class described comprising a pair of spaced substantially U-shaped brackets, one limb of each bracket being formed with a semi-circular bowed portion to provide a seat for the gas supply pipe
10 of a gas range, clips bridging the bowed

portion of the bracket for fastening the same to the said supply pipe, a plate fixed to the brackets and forming a solid front, bottom, and a top flange, and a cover plate pivotally connected with the top flange and adapted to normally rest upon the brackets. 15
